BUILDING UNIT AND FLOOR
CONSTRUCTION

Thomas J. Foster, Ridgewood, N. J.

Application November 8, 1928. Serial No. 318,065

13 Claims. (Cl. 72—66)

This invention relates to sound-proof floor construction having permanent forms incorporated therein, and aims to provide such forms adapted to be made in sections of considerable size in advance of use and to be shipped and handled as unitary slabs, which may be supported on or permanently secured between floor beams, and subsequently filled and covered with concrete, whereby the form unit becomes incorporated into the floor slab as an integral element of the permanent floor structure. If desired, the bottom face of the form unit may be painted, plastered or otherwise finished, either before or after being incorporated in the slab, to constitute the permanent ceiling of the story below, of which it may form a considerable portion of the exposed surface.

The aims of my invention include the provision of a light but strong combined form and floor slab element having sound and heat-insulating qualities cheaply manufactured of readily available local materials, so constructed as to stack conveniently, and not to be injured by handling and by exposure before use, adapted to be easily and quickly positioned for use, capable of supporting the weight of workmen walking thereon before the concrete has been poured, not susceptible of injury by the wet concrete, and having one face adapted to become the major area of the finished ceiling below.

My invention also includes the provision of means for attaching such form and floor slab elements to the floor beams or joists, and thereby producing a continuous floor and ceiling construction needing only the floor finish to make it complete.

A preferred embodiment of my invention is described in the following specification and illustrated in the accompanying drawing, wherein like reference characters refer to the same parts throughout, and wherein

Fig. 1 is a top plan view of my floor form unit;

Fig. 2 is a view in perspective, including a part of the completed floor structure; and

Fig. 3 is a partial perspective and partial section of a floor prior to placing the concrete or other plastic material, showing a method of attaching the form to a floor beam.

Referring particularly to Fig. 1, my improved form unit may conveniently be about four by eight feet, although the dimensions are of course subject to variation as desired. The preferred embodiment comprises a plurality of transverse sleepers 11, ordinarily wooden, constituting the foundation of the entire form. Each of these

is coated on the bottom with a layer of binder 12, such as asphalt, having adhesive and sound-deadening properties. A unitary sheet 13 of stiff material coextensive with the full area of the form is attached to the sleepers by the binder 12. The gypsum wallboard commercially known as "Sheetrock" has proved satisfactory for this purpose on account of its properties as an insulator of sound and heat, although I do not limit myself to any specific material. The bottom surface of the sheet 13 may be left in natural finish, while the top surface may be given a waterproof coating 14, which prevents injury to the sheet 13 during transportation and erection, and may also have an additional sound-proofing effect.

Wire reinforcement 15, herein shown as welded fabric of rectangular mesh, is fastened to the tops of the sleepers 11, being dropped between the sleepers, as shown in Fig. 2, to a suitable distance above the sheet 13. Besides reinforcing the concrete in the completed construction, this mesh work takes care of loads during the progress of the building, such as the weight of persons stepping on the forms between the sleepers.

Light longitudinal strips 16 may be nailed to the tops of the sleepers 11 near their ends, to stiffen the form element, to provide a convenient hold at each edge for handling, and as spacers to keep the forms separated when stacked, thus avoiding injury to the bottom face of the sheet 13 by the wires 15 of an adjacent lower form. The strips 16 may constitute screeds for leveling the concrete to secure a level floor of uniform thickness, and may also serve as nailing strips for securing a wooden floor.

A convenient method of fastening my improved form element to the floor beams is shown in Fig. 3, wherein an I-beam floor joist 17 is illustrated. The I-beam is fitted with a pair of nailing blocks or supporting members 18 on opposite sides, said blocks being shaped to fit the beam, and being supported partly by the bottom flange thereof and partly by a metal stirrup 19 across the beam top, and fastened to each block 18 near the top. A notch 20 is cut in the upper outer corner of each block to receive the edge of the sheet 13 and the end of a sleeper 11. Each pair of blocks 18 is tied together beneath the beam 17 by a strip 21. Side and bottom casings 22 and 23 are secured to the nailing blocks, lengthwise of the beam. The space so enclosed may be filled with concrete or other plastic material, either for strengthening or for fireproofing, if

desired, although such filling is not essential to the use of my invention.

In constructing a floor embodying the principles of this invention, pairs of nailing blocks 18 are placed along the floor beam 17 at proper intervals to receive the ends of the sleepers 11. The floor form units are then set between the beams, with the sleeper ends resting in the notches 20, and these ends may be nailed to 10 their respective blocks, for example, as shown in Fig. 3.

After the form units have been fastened in place they are filled with concrete 24, or other hardening plastic material having the requisite 15 strength, in the usual manner, and the concrete is levelled off. When the form is provided with nailing strips 16 constituting screeds, they may be filled level with the tops of such strips or screeds 16. At this stage of the operations 20 sleepers 11 hold the form rigid, preventing the sheet 13 from being bulged by the weight of the green concrete poured thereon. The sleepers and screeds are subsequently useful as nailing strips if a wooden floor is to be laid over the 25 concrete.

The invention is applicable to different kinds of floors, and is not restricted to the specific embodiment shown in the drawing.

I claim the following as my invention:

30 1. A preformed floor and ceiling slab comprising, in combination, a sheet of preformed board-like material, a waterproofing layer on the upper surface thereof, a plurality of transverse supports adhesively secured to the upper surface 35 thereof, reinforcing means attached to said supports and spaced from said boardlike material, connecting strips disposed above and transversely of said supports and above said reinforcing means, said slab being adapted to be filled with concrete above said waterproofing layer to the tops of said connecting strips.

2. A sound proof and heatproof floor and ceiling construction comprising joists and bays, each of said bays comprising a slab of reinforced concrete incorporated with a self-supporting 45 form, said form comprising a plurality of transverse supports carried by said joists, a layer of insulating adhesive on the bottoms thereof, a sheet of wall board secured therebeneath by 50 said adhesive, a waterproofing insulating layer on the upper side of said sheet, an extended reinforcing element carried by said supports in spaced relation to said sheet, connecting strips secured across the tops of said supports, and 55 concrete filling in said form above said sheet and between said joists.

3. In a building construction comprising joists and permanent pre-assembled forms, supporting elements between said joists and said forms comprising blocks or supporting members arranged at intervals along said joists in pairs 60 perpendicularly to said joists, each member of said pairs being secured to its companion by a top stirrup, and providing a seat for the edge of an adjacent form.

4. In a building construction comprising I-beams and permanent pre-assembled forms, supporting elements between said I-beams and said forms comprising blocks or supporting members arranged at intervals along said I-beams in pairs perpendicularly to said I-beams and supported by the bottom flange thereof, each member of said pairs being secured to its companion by a top stirrup and having its lower inner edge 65

notched to receive the adjacent flange of the I-beam.

5. A pre-assembled floor form unit comprising, in combination, a plurality of parallel sleepers, reinforcement therebetween, handling strips connected perpendicularly to said sleepers, and a sheet of stiff material attached beneath said sleepers constituting the bottom of said form unit.

6. A pre-assembled floor form unit comprising, in combination, a plurality of parallel sleepers, reinforcement therebetween, handling strips connected above said sleepers, crosswise thereof, and a sheet of stiff material attached beneath said sleepers constituting the bottom of said form, said form being adapted to be permanently secured between joists and to be filled with plastic material for embodiment in the permanent floor structure.

7. A pre-assembled floor form comprising, in combination, a plurality of parallel transverse sleepers, reinforcing means therebetween and resting thereon, the portions of said means between said sleepers lying near the plane of the bottoms thereof, a substantial thickness of sound-deadening binder on the bottoms of said sleepers, a sheet of stiff material adhesively secured thereby, and a sound-deadening waterproof coating on the upper surface of said material.

8. A pre-assembled floor form comprising, in combination, a plurality of parallel transverse sleepers, reinforcing means therebetween and resting thereon, the portions of said means between said sleepers lying near the plane of the bottoms thereof, a substantial thickness of sound-deadening binder on the bottoms of said sleepers, a sheet of stiff material adhesively secured thereby, and a sound-deadening waterproof coating on the upper surface of said material, said form being adapted for positioning between the beams of a floor and to be filled with cementitious material, thereby constituting a permanent portion of the floor, said sheet of stiff material being adapted to constitute a sound-deadening ceiling.

9. A sound proof and heatproof floor and ceiling construction comprising joists and bays, each of said bays comprising a slab of reinforced concrete incorporated with a self-supporting 125 form, said form comprising a plurality of transverse supports carried by said joists, a layer of insulating adhesive on the bottoms thereof, a sheet of wall board secured therebeneath by said adhesive, said sheet of wall board being 130 adapted to constitute a sound-deadening ceiling, and concrete filling in said form above said sheet and between said joists.

10. In a building construction comprising joists and permanent pre-assembled forms comprising, in combination, a plurality of parallel sleepers, reinforcement therebetween, and a sheet of stiff material attached beneath said sleepers,

supporting elements between said joists and said forms comprising blocks or supporting members arranged at intervals along said joists in pairs perpendicularly to said joists, each member of said pairs being secured to its companion by a top stirrup, and providing a seat for the edge of an adjacent form.

11. In a building construction comprising flanged beams and pre-assembled forms adapted to be secured therebetween, connecting elements between said forms and said beam comprising blocks or supporting members the lower por-

tions of which rest on flanges of said beams and the upper portions of which support the edges of said forms, and a filling of fireproof material embedding said blocks and forming therewith a continuous insulation for the web of said beams.

12. In a building construction comprising flanged beams and pre-assembled forms adapted to be secured therebetween, connecting elements between said forms and said beams comprising blocks or supporting members the lower portions of which rest on flanges of said beams and the upper portions of which support the edges of said forms, said blocks being arranged in pairs on opposite sides of said beams and connected together above and below said beams.

13. A pre-assembled floor form comprising, in combination, a plurality of parallel transverse sleepers, reinforcing means therebetween and resting thereon, the portions of said means between said sleepers lying near the plane of the bottoms thereof, a sheet of stiff material attached beneath said sleepers constituting the bottom of said form unit, said form being adapted for positioning between the beams of a floor and to be filled with cementitious material, thereby constituting a permanent portion of the floor, said sheet of stiff material being adapted to constitute a lamination in the floor and thus to reduce transmission of sound through the floor.
